UNITED STATES PATENT OFFICE.

SAMUEL M. COZAD, OF LOS ANGELES, CALIFORNIA.

SAFETY DEVICE FOR LAUNDRY MACHINES.

Application filed April 18, 1922. Serial No. 555,346.

To all whom it may concern:

Be it known that I, SAMUEL M. COZAD, a citizen of the United States, residing at Los Angeles, in the county of Los Angeles and State of California, have invented new and useful Improvements in Safety Devices for Laundry Machines, of which the following is a specification.

This invention relates to power driven laundry washing machines, and more particularly the invention pertains to a safety appliance therefor.

It has been found that inexperienced and careless operatives will attempt to start the machine before the cylinder lids have been closed down and also before the hand setting mechanism, by which the cylinder is brought to a position to register the doors with the shell covers, has been disconnected as from the main gear on the cylinder shaft.

It is an object of the present invention to provide a safety appliance rendering it impossible to start the operation of the machine until the cylinders have been closed.

It is further an object to utilize the same safety mechanism to prevent starting of the machine when the hand setting mechanism is in effective position. A further object is to provide a safety appliance that can be readily applied to installed machines with but little expense and without substantial change of construction of the same, and which appliance can be readily combined with machines in the course of manufacture and completed machines.

One embodiment of the invention is herein described and illustrated in the accompanying drawings, in which—

Figure 1 is a front elevation of one form of washing machine, parts of which are broken away.

Fig. 2 is a detail perspective of certain elements of the safety appliance.

Fig. 3 is an end elevation of the right hand end of the machine of Fig. 1; the parts being broken away.

Fig. 4 is a perspective of one of the safety levers of the machine.

Fig. 5 is a plan of the machine, parts of which are broken away.

Fig. 6 is a plan of one of the latches for retaining a cover in uplifted position.

The machine as shown comprises an exterior stationary cylindrical drum or shell 2 arranged on a horizontal axis and supported in a suitable framework, parts of which are

shown at 3. This shell may be provided with one or more cover sections 2^a movable in the direction of the arrow in Fig. 1 to permit access into the interior of the shell 60 in which there is arranged one or more washing cylinders 4. The cylinders or cylinder sections are provided with one or more cover members 4^a ordinarily hinged as at 4^b to one side of the opening 5 provided therefor so that the covers may be lifted to permit access into the interior of the cylinder 4 for loading and unloading the same.

The cylinder 4 is rotated ordinarily in alternating motions and this is accomplished by the driving of the shaft 6 upon which the cylinder is mounted, first in one direction and then in the opposite. This rotary movement is secured in the present case by a large gear 7 fastened on one exposed end 65 of the shaft 6 and which gear meshes with an intermediate gear 8 of a transmission train including a pinion 9 driving the gear 8.

The pinion shaft and its train of gear is adapted to be driven by any suitable form 80 of mechanism which, in the present case, includes a fixed pulley wheel 10, Fig. 5, on the sides of which are arranged loose pulleys 11 and 12. These pulleys are driven by straight and twisted belts 13 and 14 85 which are shiftable to and from the tight pulley as by shifting device 15, all of which forms part of well known mechanism not herein claimed.

The starting and stopping operation of 90 the gear train is controlled by a lever 16, and this is under the control of the operative who can throw the lever 16 to a starting and to a stopping position by means of an extended handle or rod 17 reaching over 95 to the front of the machine and being pivotally connected at 18 to the control lever 16.

It frequently happens that when the machine is stopped by throwing over the lever 16, the covers 4^a of the cylinders are located 100 out of register with the opening in the shell beneath the cover 2^a, and means are usually provided in these large machines to manually rotate the cylinder to bring its cover 4^a into register with the shell or casing 105 opening so that the cylinder cover can be reached and lifted to uncovering position, as shown to the left in Fig. 1, and as shown in Fig. 3. Such a positioning means may consist of a pinion 20 secured to a crank 110 handle 21 and which pinion is slidable along a stud or trunnion 22 projecting from one

end of the machine frame. By means of the crank 21 the pinion 20 can be rotated after it has been shifted into mesh with the gear 7 so as to work the gear around 5 and bring the cylinder covers below the shell openings.

Novices and careless operatives may attempt to start the operation of the machine before the pinion 20 has been shifted out 10 of mesh with the driven gear 7 of the cylinder, and this results in accidents to the machine and to the operative because of the high rate at which the small pinion will be driven by the large gear when it is 15 turned by the power train.

To avoid such accidents, my invention includes means controlling the starting of the driven train so long as the pinion 20 may be in mesh with the gear 7. A form 20 of means is shown as including a safety lever 25 mounted intermediately on a pivot 26 provided on the frame of the machine. The safety lever 25 has an offset front end to pass under the hub 20' of the pinion 20 25 when the latter is in gear meshing position and at which time the lever 25 will be held down at its outer end while its opposite end is thrust upwardly and carries a stop rod 27 upwardly through a guide 28 provided on the frame and in which the stop rod 27 is slidable. In its upper position, as shown in Fig. 3, the stop rod stands 30 in front of a lock pin 29 which is provided on one side of the starting handle 17; this 35 being pushed back to throw the starting lever 16 to stopping position. It will be seen that when the safety lever 25 is pushed down below the hub 20', it will therefore thrust the stop rod 27 upwardly in front of the lock pin 29 of the handle 27 when 40 this is in the rearward position, see Fig. 3. Before the operator can start the machine he will therefore have to disconnect the pinion 20 from the gear 7 by sliding the 45 pinion outwardly along its trunnion 22 during which time the hub 20' of the pinion will be shifted from position above the safety lever 25 and this, as soon as it is thereby released, will swing downwardly at its rear 50 end carrying with it the stop rod 27, the upper end of which will recede from effective position in front of the lock pin 29. Therefore the operator can then, and then 55 only, pull the starting handle 17 forwardly to draw into operation the driving train connected to the gear 7.

The starting lever 16 with its handle 17 is also controlled by the stop pin 29 to prevent the operator from starting the machine until such of the cylinder covers 4^a as may be opened have been thrown into the closed position in its opening 5 of its cylinder 4.

To that end the lock pin 29 is shown in 60 Fig. 5 as extending through the starting

handle 17 and is adapted to be engaged by a stop rod 30 mounted in the guide 28. The lower end of the stop rod 30 is connected to an arm 31 which is secured upon the contiguous end of a rock shaft 32 journaled in suitable bearings 33, and which rod extends longitudinally of the machine in a position above the top of the casing or shell 2.

Mounted upon the bearings 33 of the rock 75 shaft 32 is a pair of latches each of which has a hook end 34 and each of which is formed of a yoke shape in end view as shown in Fig. 3. The yoke arms are laterally extended to form ears 35 straddling the bearings 33 and receiving a pivot pin 36, of which there is one in each bearing for each latch 34. There are as many latches arranged along the machine as there are cylinder covers 4^a, and as each cover is lifted 80 through the shell, one edge of the cover is adapted to engage the hook 34 and this is swung outwardly until the edge of the cover passes behind the shoulder of the hook and the cover is retained in elevated position as 85 shown to the left in Fig. 5. Each latch is thrown to the effective position as by means of a contractile spring 37, one end of which is attached to a latch and the opposite end is fastened to its bearing or bracket 38. 90 Thus the latches hold the covers in uplifted position.

As the covers are lifted, they respectively engage means for rocking the rock shaft 32 so as to tilt the lever 31 which will thus 100 raise the stop rod 30 into a position in front of the contiguous portion of the lock pin 29, while the starting handle 17 is pushed rearwardly; it being understood that the driving mechanism is in idle position while the 105 covers are elevated.

Means for thus rocking the rock shaft 32 and which means are controlled by the covers 4^a consist, in the present case, of dogs 38 in the form of an L-shaped member, Fig. 4, 110 provided at the front end of a yoke 39 from which the dog 38 extends laterally at the intermediate portion of the yoke. The yoke arms are mounted upon the pivot pin 36 upon which the latches 34 are mounted, it 115 being understood that the yokes 39 of the dogs 38 overlap the latch yokes as clearly shown in Fig. 3. As a cover 4^a is thrown to the open position, its edge will engage the contiguous end of the dog 38 located thereat 120 and the dog will be swung to the outer position. Each of the dog yokes 39 is provided with a trip arm 40 and this trip arm is disposed so as to engage a downwardly extending abutment arm 41, of which there is one 125 secured to the rock shaft 32 for each of the dog yokes 39. Thus, as the dog yoke is swung on its pivot the trip arm 40 swings rearwardly against the contiguous abutment arm 41 and the shaft 32 is rocked thus lifting 130

the rod arm 31 from dotted position, Fig. 3, to full line position carrying the stop rod 30 into effective position in front of the lock pin 29, thereby preventing the starting handle 17 from being pulled inwardly until the covers 4^a have been lowered into the cylinder thereby releasing the tripping dogs 38 to bring the trip arms 40 to neutral position and release the abutment arms 41 and thereby the rod arm 31.

From the above it will be seen that I have provided a comparatively simple means providing for the locking of the starting mechanism against the same being thrown into operation while the hand operated cylinder means is in effective position and also while any of the covers of the cylinders are in open position.

It is to be understood that while the present invention has been shown in combination with a laundry washing machine, it may be readily incorporated with various other types of machines in which it is desirable to provide safety appliances to control starting and stopping operation of the given machine.

Various changes and modifications may be made without departing from the spirit of the invention as claimed.

30 What is claimed is:

1. In a power driven washing machine, a washing cylinder provided with a cover member adapted to be lifted and having power means for driving the cylinder including belts and tight and loose pulleys, and means for shifting the belts to stop and start the cylinder, means for preventing the starting of the power means while the cover member of the cylinder is in lifted position, said means comprising mechanism for holding the cover open and adapted to hold the belts from shifting while the cover is open.

45 2. In a power driven washing machine having a cylinder with a cover member adapted to be lifted for access to the cylinder, power means for driving the cylinder and including shifting belts and tight and loose pulleys and a belt shifter, and a safety device for preventing the starting of the power while the cover member is open, comprising a dog yoke pivotally mounted to be engaged by the cover member, a rock

shaft suitably supported and operated by the dog yoke, a stop rod operated by the 55 rock shaft, and a lock pin on the belt shifter engaged by the stop rod.

3. In a power driven laundry washing machine having a cylinder provided with movable cover means, a power driven train 60 connected to the cylinder and including a starting and stopping instrumentality, manual means for rotating the cylinder to bring the cover means to a predetermined position when the power is cut off, and safety mechanism for preventing the starting of the power driven means while the said manual means is in effective position and while the cover means of the cylinder is in an uplifted 65 position.

4. In a power driven laundry washing machine having a cylinder provided with movable cover means, a power driven train connected to the cylinder and including a starting and stopping instrumentality, manual means for rotating the cylinder to bring the cover means to a predetermined position when the power is cut off, and safety mechanism for preventing the starting of the power driven means while the said manual 80 means is in effective position and while the cover means of the cylinder is in an uplifted position, the said safety mechanism having parts respectively controlled by the manual means and by the cover means.

5. In a power driven laundry washing machine having a cylinder provided with movable cover means, a power driven train connected to the cylinder and including a starting and stopping instrumentality, manual means for rotating the cylinder to bring the cover means to a predetermined position when the power is cut off, and safety mechanism for preventing the starting of the power driven means while the said manual 90 means is in effective position and while the cover means of the cylinder is in an uplifted position, the said safety mechanism having parts respectively controlled by the manual means and by the cover means so that the 100 starting mechanism is controlled by either the manual means or the cover means.

In testimony whereof I have signed my name to this specification.

SAMUEL M. COZAD.
